UNITED STATES PATENT OFFICE.

GEORGE C. VANMEER, OF BURK'S FALLS, ONTARIO, CANADA.

MOVING-PICTURE MACHINE.

1,171,485.

Specification of Letters Patent. Patented Feb. 15, 1916.

Application filed April 12, 1915. Serial No. 20,826.

To all whom it may concern:

Be it known that I, GEORGE C. VANMEER, subject of the King of England, residing at Burk's Falls, in the Province of Ontario, 5 Dominion of Canada, have invented certain new and useful Improvements in Moving-Picture Machines; and I do hereby declare the following to be a full, clear, and exact description of the invention, such as will 10 enable others skilled in the art to which it appertains to make and use the same.

This invention relates to new and useful improvements in moving picture machines.

An object of the invention resides in the 15 provision of a device by means of which the film may be kept taut during the feeding of the same from one roll to the other so that the film at the shutter will be prevented from buckling.

20 With this and other objects in view, such as will appear as the description progresses, my invention comprises the combination and arrangement of parts as set forth in and falling within the scope of the appended 25 claims.

Referring to the drawing:

Figure 1 is a front elevation of my device, showing the same attached to a projecting machine. Fig. 2 is a side elevation thereof. 30 Fig. 3 is a vertical sectional view taken through the film. Fig. 4 is a plan view.

Referring to the drawing wherein like parts are indicated by like characters throughout the several views: in the embodiment of my invention shown in the drawing I have provided a pair of rollers 1 and 2 which are disposed horizontally and in vertical alinement. The uppermost roller is adapted to be mounted upon the frame 35 of the projecting machine by means of brackets 3 so that it will be freely rotatable. The lowermost roller 2 is suspended, by means of springs 4, from the roller 1, which springs normally maintain the roller 2 in 40 contact with the roller 1 when there is no film therebetween. A pair of similar rollers 5 and 6 are provided. The roller 6 is rotatably mounted on brackets 7, which are adapted to be secured to the frame of the 45 machine. The roller 5 is mounted on springs 8 which extend from the roller 6 and on which the roller 5 is rotatable. These springs 8 normally maintain the roller 5 in engagement with the roller 6 when there 50 is no film disposed between them. Extending 55 between the rollers 2 and 5, at the ends

thereof, are springs 9 which normally tend to force the rollers 2 and 5 toward the respective adjacent rollers 1 and 6.

In using this device the best results are 60 obtained by the use of a film 10 which winds from a spool 11 onto a second spool mounted within a film magazine 12. This film has a binding strip 13 on each edge thereof, which strip may be made of rubber, leather 65 or any other suitable material. These strips protect the film and prevent it from tearing.

In operation the film 10 is fed from the spool 11, between the rollers 1 and 2, is then carried downwardly and between the rollers 5 and 6 onto the second spool. During the movement of the film from the spool 11 to the spool 12 the rollers 1 and 2 and the rollers 5 and 6 will be held resiliently against the faces of the film or the binding strips 70 on the edges thereof by the springs 4 and 8, respectively. During this movement of the film the portion disposed between the rollers 2 and 5 will be kept taut by the action of the springs 9, which tend to separate the rollers 2 and 5, and, because of the presence of the binding strip 13 on the film, will prevent the buckling of the film between these rollers. Thus this portion of the film, which is the 75 portion which is exposed to the light, is kept taut and consequently the projecting of the figures will be constant.

From the foregoing description it will be seen that I have provided a device for 80 maintaining the portion of a film, on a moving picture machine, through which the light is projected, taut so that the buckling of the film will be prevented.

While I have illustrated and described a 85 particular embodiment of my invention, I have merely done so for the sake of convenience and I do not wish to be limited to that particular embodiment as it is obvious that numerous changes may be made within 90 the details of construction thereof without 100 in any way departing from the spirit of the invention or exceeding the scope of the appended claims.

What I claim is:—

1. In a device for maintaining a moving 105 elongated film taut, a pair of horizontally disposed rollers, means for resiliently pressing said rollers together, a second pair of horizontally disposed rollers located beneath 110 and in spaced relation to the first mentioned rollers, means for pressing said last mentioned rollers, resiliently, together, and resil-

ient means for forcing the adjacent rollers of the pairs, apart.

2. In a device for maintaining an elongated moving film taut, a roller, brackets for supporting said roller, a second roller located beneath the first mentioned roller, springs connected to said rollers to press the same together, a pair of rollers disposed beneath the first mentioned rollers and re-

silient means for normally forcing the first 10 mentioned rollers and the last mentioned pair of rollers apart.

In testimony whereof, I affix my signature, in the presence of two witnesses.

GEORGE C. VANMEER.

Witnesses:

ELIZABETH M. WEIS,
GEORGE FREEMAN.
